FROZEN STORAGE TRAY AND MOUNTING

Floyd R. Eck, Des Plaines, Ill., assignor to Motor Products Corporation, Detroit, Mich., a corporation of New York

Application July 16, 1951, Serial No. 237,019

5 Claims. (Cl. 62—89)

1

This invention relates generally to refrigerator cabinet structures, and refers more particularly to an improved storage tray for use in connection with refrigerator cabinets.

It is an object of the present invention to provide a removable storage tray, which when assembled into the cabinet of a refrigerator, performs the following functions: (1) serves as a heat insulating baffle between the cooling element or evaporator and the storage space within the cabinet; (2) collects moisture which drips from the evaporator during the defrosting operation; and (3) serves as a storage space for articles it is desired to maintain at a temperature somewhat lower than the temperature existing in the storage space.

It is another object of this invention to provide a tray having a main bottom wall and a supplemental bottom wall coacting with the main bottom wall to form a space therebetween for accommodating heat insulating material.

It is still another object of this invention to provide a tray wherein the supplemental bottom wall is formed separately from the main bottom wall, and is secured to the latter wall in a manner to provide a fluid-tight seal around the space containing the heat insulating material.

It is a further object of this invention to provide a tray of the above type wherein the supplemental bottom wall is in the form of an inverted pan-shaped section, and wherein the side and end walls of the supplemental bottom wall coact with the side and end walls of the tray to provide a channel within the tray around the supplemental wall for accommodating moisture dripping from the evaporator. Thus articles may be supported on the supplemental wall without coming in contact with any moisture that may accumulate in the tray.

The foregoing as well as other objects will be made more apparent as this description proceeds, especially when considered in connection with the accompanying drawings, wherein:

Figure 1 is a fragmentary front elevational view of a refrigerator cabinet showing the door removed and illustrating the storage tray embodying the features of this invention;

Figure 2 is a sectional view taken on the line 2—2 of Figure 1;

Figure 3 is a sectional view taken on the line 3—3 of Figure 1;

Figure 4 is a sectional view taken on the line 4—4 of Figure 3;

Figure 5 is a perspective view showing the evaporator; and

2

Figure 6 is an enlarged cross sectional view through the storage tray.

In Figure 1 of the drawings, the upper portion of a refrigerator cabinet 10 is shown with the usual door removed for the sake of clearness. The cabinet 10 comprises an outer shell 11, an inner shell 12 spaced laterally from the outer shell, and heat insulation 13 interposed between the shells. The front edges of the two shells are connected by a front wall 14 preferably formed of a heat insulating material and defining an access opening 15 which is normally closed by a suitable hinged door not shown herein.

The interior of the cabinet is refrigerated by suitable refrigerating apparatus including an evaporator 16 suitably supported within the cabinet 10 adjacent the top of the latter. The remaining parts of the refrigerating apparatus including the condenser, motor-compressor unit, etc. may be of any type well known to the industry, and hence are not shown herein.

The evaporator 16 comprises a sheet metal casing 17 which is of a dimension to extend substantially the full width and depth of the interior of the refrigerator cabinet 10. The casing 17 has top, side, rear and bottom walls 18, 19, 20 and 21 respectively. The front wall of the casing is open, and is normally closed by an insulated door 22 suitably hinged at the bottom for outward swinging movement to provide access into the interior of the casing.

The side walls 19 and the rear wall 20 project upwardly beyond the top wall 18 and cooperate with the latter and top wall of the inner shell 12 to form a space 23 for accommodating ice trays or other articles to be maintained at a relatively low temperature. The door 22 is of sufficient width to close both the access opening in the front wall of the casing and the space 23, as clearly shown in Figure 1 of the drawings.

In addition the evaporator embodies a continuous length of coiled tubing 24 having three sections 25, 26 and 27. The section 25 is brazed or otherwise suitably secured to the underside of the top wall 18 of the cabinet 17, and has one end 28 which projects through the rear wall 20 of the casing. The end 28 of the section 25 is connected to one end 29 of the section 27, and the latter is brazed or otherwise suitably secured to the underside of the bottom wall 21 of the casing 17. The other end 30 of the section 27 is connected to the lower end of the section 26, which is brazed or otherwise secured to the rear wall 20 of the casing 17. The upper end of the section 26 is connected to a suitable accumulator 31, and

the latter is connected to the refrigerant supplying apparatus (not shown) by a suction line 32. Refrigerant is supplied first to the section 25 through a drier or dehydrator 33 suitably fixed to one side wall 19 of the casing 17, and the drier or dehydrator 33 is connected to the refrigerant supply apparatus by a capillary tube not shown herein.

The efficiency of the evaporator 16 in maintaining the atmosphere within the casing 17 and space 23 at relatively low temperatures is improved by providing a baffle in the form of a storage tray 36 directly below the bottom wall 21 of the evaporator, and thereby prevent the warmer air in the storage space 34 beneath the tray 36 from coming in direct contact with the bottom wall of the evaporator. The storage tray 36 may be formed of various different materials but is preferably formed of plastic or some equivalent heat insulating material. The tray 36 is dimensioned to extend substantially throughout the full width of the storage space 34, and throughout the full depth of the evaporator 16. As shown in Figure 6 of the drawings, the tray comprises two sections 37 and 38. The section 37 is open at the top and has side, end, and bottom walls 39, 40 and 41 respectively. The section 38 is in the form of an inverted pan-shaped part also having side, end, and bottom walls 42, 43 and 44 respectively.

The section 38 is supported within the section 37, and forms a supplemental bottom wall of the tray 36. Referring again to Figure 6 of the drawings, it will be noted that the top of the bottom wall 41 is formed with a recess 45 dimensioned to coact with the inverted pan-shaped section 38 to form an enclosed space 46 of substantial depth for accommodating a relatively thick batt of heat insulating material 47. It will be noted that the recessed portion of the bottom wall 41 is fashioned with upstanding ribs 48 which serve to effectively reinforce the wall 41. Similar ribs 49 may also be formed on the wall 44 of the section 38, if desired.

The side and end walls 42 and 43 respectively of the section 38 are formed with laterally outwardly extending flanges 50 which seat on the top surface of the bottom wall 41 around the recess 45. The flanges 50 are fashioned with a depending rib or projection 51, which extends continuously around the recess 45, and projects into a groove 52 formed in the adjacent portion of the bottom wall 41 of the tray. The projection 51 and the side walls of the groove 52 are correspondingly tapered in a direction to facilitate inserting the projection into the groove. In any case the contacting surfaces of the flange 50 and bottom wall 41 are cemented together by a suitable plastic cement 53 in order to secure the supplemental bottom wall 38 to the bottom wall 41 of the tray section 37 and to also provide an effective fluid-tight seal around the space 46 for the insulating material 47.

In use the tray 36 is removably supported in the storage space 34 directly below the bottom wall 21 of the evaporator casing 17. For accomplishing this result a pair of guides 54 are respectively secured to opposite sides of the liner 12 by fastener elements 55. The guides are preferably formed of a suitable plastic material, and each guide is provided with vertically spaced channels 56 for selectively slidably receiving flanges 57, which extend laterally outwardly from opposite side walls 39 of the tray section 37. The purpose of the vertically spaced

channels is to enable supporting the storage tray 36 in different vertical positions with respect to the evaporator 16, and thereby vary the depth of the space between the bottom of the evaporator and the tray 36. Thus a greater or lesser amount of air circulates through the space directly below the evaporator 16 and the rate of cooling of air in the storage space 34 is controlled accordingly.

The tray 36 is free to slide forwardly from the position thereof shown in Figure 2 of the drawings through the access opening 15 in the cabinet 10 to a position wherein the articles supported within the tray are readily accessible. This position of the tray 36 is determined by lugs 58 projecting downwardly from the flanges 57 adjacent the rear end wall 40 of the tray and engageable with stops 59 projecting upwardly from the guides 54 adjacent the front ends of the latter. The height of the stops 59 is so determined with respect to the depth of the guide channels 56 to permit completely removing the tray 36 by merely raising the same off the guides sufficiently to enable the projections 58 to clear the stops 59.

In order to facilitate handling the tray 36 and also improve the appearance of the tray, a handle 60 of extruded aluminum, for example, is secured to the front end wall 40 of the tray 36 adjacent the top thereof. Also the appearance of the tray is improved by extending the front end wall 40 laterally beyond the opposite side walls 39 a distance approximating the width of the flanges 57. As a result the flanges 57 and a substantial part of the guides 54 are concealed from view when the tray is in its operative position.

As shown in Figures 1 and 2 of the drawings, the tray 36 is supported in close proximity to the bottom wall 21 of the evaporator casing 17, and the top of the tray is open so that the contents are cooled to a relatively low temperature by the evaporator. The insulated bottom wall of the tray retards the transfer of heat from the storage space 34 into the interior of the tray, and also acts as a baffle to direct air circulating in the space 34 away from the bottom of the evaporator. In addition the tray serves to collect moisture dripping from the evaporator during the defrosting operation; and in this connection, it will be noted that the supplemental bottom wall 38 is elevated to provide a continuous channel at the bottom of the tray for receiving the moisture. As a result moisture collected by the tray is prevented from contacting articles supported on the supplemental wall 38.

What I claim as my invention is:

1. A baffle member for installation in a refrigerator cabinet between a food storage compartment and a cooling unit in the cabinet above the storage compartment, comprising a tray open at the top and having side, end and bottom walls, a supplemental bottom wall cooperating with the bottom wall of the tray to provide an enclosed space and having a marginal portion seated on the bottom wall of the tray, and a rib surrounding the enclosed space and projecting from one of said bottom walls into a groove in the other of said bottom walls, said rib and groove having adjacent surfaces integrally secured together in continuous sealing contact throughout the length of the rib.

2. A baffle member for installation in a refrigerator cabinet between a food storage compartment and a cooling unit in a cabinet above the

storage compartment, comprising a tray having side, end and bottom walls, a supplemental bottom wall located within the tray in vertical spaced relationship to the bottom wall of the tray and having depending side and end walls coacting with the bottom wall of the tray to provide an enclosed space, and an upwardly opening recess in the bottom wall of the tray registering with the enclosed space and substantially increasing the depth thereof.

3. The structure defined in claim 2 wherein the side and end walls of the supplemental bottom wall has a continuous marginal surface arranged in sealing contact with an adjacent surface of the bottom wall of the tray surrounding said recess, and a rib surrounding the recess and projecting from one of said bottom walls into a groove in the other of said bottom walls.

4. A heat insulating member for installation in a refrigerator cabinet between a food storage compartment and a cooling unit in the cabinet above the storage compartment, comprising a tray supported within the compartment and having side, end and bottom walls, a supplemental bottom wall located within the tray in vertical spaced relationship to the bottom wall of the tray and having depending side and end walls spaced laterally inwardly from the corresponding walls of the tray to provide a channel within the tray around the supplemental bottom wall,

and marginal portions projecting laterally outwardly from the side and end walls of the supplemental bottom wall, said portions cooperating to form a continuous marginal flange having a sealing contact throughout its length with the bottom wall of the tray and integrally secured to said bottom wall of the tray to provide a unitary structure.

5. The structure defined in claim 4 wherein the bottom wall of the tray has an upwardly opening recess within the confines of the marginal portions and registering with the enclosed space to increase the depth of the latter, and heat insulating material located between the bottom wall of the tray and said supplemental bottom wall.
